UNITED STATES PATENT OFFICE.

GEORGE W. NIBBE, OF CHICAGO, ILLINOIS.

TIE-PLATE.

1,389,686.

Specification of Letters Patent. Patented Sept. 6, 1921.

Application filed November 29, 1920. Serial No. 426,910.

To all whom it may concern:

Be it known that I, GEORGE W. NIBBE, a citizen of the United States, residing at Chicago, in the county of Cook and State of Illinois, have invented certain new and useful Improvements in a Tie-Plate, of which the following is a specification.

My invention relates to tie plates and has particular reference to a tie plate having 10 diagonally extending non-cutting tie engaging ribs on the underside, and having recesses formed in the body of the tie plate between the diagonally extending ribs which serve as cushions under the tie and lighten 15 the plate without objectionably lessening its strength. The diagonally extending ribs become embedded into the tie across the grain thereof, when the tie plate is in position upon the tie and under the rail base, so that splitting of the tie is avoided, the 20 recesses on the underside of said tie plate also assisting in preserving the tie because of its cushioning resistance to the embedding of the tie plate.

25. Another object of my invention is the provision of a tie plate having longitudinally extending marginal ribs on its underside so that moisture is prevented from entering underneath the tie plate and thereby 30 rotting the ties and the tie plate is enabled to grip the tie to a better advantage, and also having a centrally located longitudinally extending rib to which the diagonally extending ribs are joined which serves to 35 strengthen the tie plate.

Another object of my invention is the provision of a tie plate having the structural features above set forth in combination with a cambered or curved top which causes the 40 tie plate to better perform its function and enables the tie plate to become firmly seated upon the tie and serve as a part thereof, that is, the tie plate and tie do not move relative to each other, this movement, if any, being 45 between the rail and the tie plate. This form also prevents the tie plate from rattling and having its sides rocked back and forth by the movement of trains which causes the tie plate to cut into the tie and 50 destroys the fibers of the tie plate which happens when the rail bearing surface of the tie plate is flush with the rail.

Another object of my invention is the provision of a tie plate having the structural features heretofore set forth with respect to the bottom thereof and in addition thereto having the usual rail abutting shoul-

der extending transversely across the top thereof with a sloping or canted cambered surface extending downward from the side 60 of the tie plate upon which the shoulder is located to a point approximately even with the inside edge of the rail base, so that the rail is tilted slightly in order to accord a better resistance to the weight and thrust 65 of the car wheels upon the rail and to better enable the weight of the car to be transmitted on to the tie plate in a straight line.

Another and further object of my invention is the provision of a tie plate which is 70 simple in construction and which is stronger than any other tie plate of equal weight, therefore having greater resistance to buckling and affording greater resistance to track spreading because of the diagonal ribs. 75

These and other objects of my invention will be more fully and better understood by reference to the accompanying drawings, and in which—

Figure 1 is a side elevational view of my 80 improved tie plate showing the canted cambered top;

Fig. 2 is a bottom plan view of my improved tie plate; and

Fig. 3 is an end view in elevation of my 85 improved tie plate showing the canted cambered top surface.

Referring now specifically to the drawings, and in which like reference characters refer to like parts throughout, 10 is a tie 90 plate body having the usual rail abutting transversely extending shoulder 11 on the upper side thereof. As indicated at 12, the top surface of the tie plate body 10 upon which the rail base is seated is slightly 95 curved or cambered, the high portion 13 being in the middle of the said plate and curving slightly outward to the marginal edges 14 thereof, thus allowing the tie plate to 100 act as a part of the tie and move only with the tie instead of upon the tie. Beginning at the shoulder 11 the top surface of the tie plate body 10 is canted or sloped slightly to a point on the upper side of said tie plate body 10 and from this point to the edges 105 thereof the tie plate slopes downward at a slightly greater degree, thus lengthening the tie plate without impairing its efficiency.

Referring now specifically to Fig. 2, which illustrates the underside of the tie plate body 110 10, I provide a pair of longitudinally extending marginal ribs 16 and 17 and a centrally located longitudinally extending rib 18. Extending diagonally across the said

- tie plate body 10 and joined to the marginal rib 16 at one end and to the rib 18 at their other ends are a plurality of diagonally extending spaced tie engaging ribs 19, the said 5 ribs being on one side of the bottom of the tie plate body, other ribs 20 joined to the marginal rib 17 and to the central rib 18, the said ribs 20 joining the rib 18 at points opposite the ends of the ribs 19 where they 10 join the central rib 18. Between the ribs 19, the marginal rib 16 and the central rib 18 are a plurality of recesses 21 extending into the tie plate body 10, these recesses being arcuate in cross-sectional shape and therefore 15 deepest at their central portions. The recesses 21 extend parallel with the ribs 19 and have their side edges spaced from the ribs 19 a short distance and their ends spaced apart from the said ribs 16 and 18. 20 Similar recesses 22 are provided between the diagonally extending ribs 20, the marginal rib 17 and the central rib 18 on the opposite side of the tie plate bottom. The recesses serve as cushions and in conjunction with the spaces between them and the ribs prevent excessive embedment of the tie plate into the tie. 25 The construction of the recesses parallel with the ribs 19 and with the added strength 30 of the ribs and the spaces between the recesses and the ribs, prevents the tendency to buckle, which is ordinarily found in the tie plates with corrugated tops or bottoms. By adding about half of the metal saved 35 by the recesses, to the rail bearing surface and behind the shoulder 11, the tie plate is given enough additional strength to make it much stronger than any other plate of equal weight. 40 It will be noticed that the ribs 19 and 20 extend diagonally across the underside of the tie plate so that the thrust outward of the tie plate tends to compress the fibers of the tie on the top surface thereof so that 45 better resistance is afforded the tie plate than if the said ribs extended in a straight line transversely across said tie plate. The tie plate by reason of its construction is rolled by what is commonly called "the 50 end over end" method, therefore permitting a true and centrally located camber to be rolled on it and also producing a tie plate of added service by reason of the rail action being against the grain of the steel. 55 While I have described more or less precisely the details of construction, I do not wish to be understood as limiting myself thereto, as I contemplate changes in form and the proportion of parts and the substitution of equivalents as circumstances may 60 suggest or render expedient without departing from the spirit or scope of my invention.
- I claim:
1. A tie plate having an upper rail receiving surface and a rail abutting flange 65
- extending transversely of the said plate, the said rail bearing surface being canted longitudinally of said plate, and a bottom tie engaging surface having longitudinally extending ribs on its marginal edges, and a 70 longitudinally extending central rib intermediate its edges, and a series of diagonally extending tie engaging ribs joined at their inner ends to the said central rib and to the marginal ribs at their outer ends and having 75 a series of recesses in the body of said tie plate between said diagonally extending ribs respectively and between the central rib and the marginal ribs. 80
2. A tie plate having an upper rail receiving surface and a rail abutting flange extending transversely thereof, the said rail bearing surface being cambered transversely of said plate, and a bottom tie engaging surface having longitudinally extending ribs 85 on its marginal edges, and a longitudinally extending central rib intermediate its edges and a series of diagonally extending tie engaging ribs joined at their inner ends to the said central rib and to the marginal ribs 90 at their outer ends and having a series of recesses in the body of said tie plate between said diagonally extending ribs respectively and between the central rib and the marginal ribs. 95
3. A tie plate having an upper rail receiving surface and a rail abutting flange extending transversely thereof, the said rail bearing surface being canted longitudinally of said plate and cambered transversely 100 thereof, and a bottom tie engaging surface having longitudinally extending ribs on its marginal edges, and a longitudinally extending central rib intermediate its edges and a series of diagonally extending tie 105 engaging ribs joined at their inner ends to the said central rib and to the marginal ribs at their outer ends and having a series of recesses in the body of said tie plate between said diagonally extending ribs respectively 110 and between the central rib and the marginal ribs. 115
4. A tie plate having an upper rail receiving surface and a rail abutting flange extending transversely of said plate and a bottom tie engaging surface having longitudinally extending ribs on its marginal edges, a longitudinally extending central rib and a series of diagonally extending tie 120 engaging ribs joined at their inner ends to the central rib and to the marginal ribs at their outer ends, the said tie plate having a series of arcuate shaped recesses extending parallel with said diagonally extending tie engaging ribs, said recesses having their 125 marginal edges spaced apart from the adjacent rib. 130

Signed at Chicago, Illinois, this 24th day of November, 1920.

GEORGE W. NIBBE.
